US0D1048808S

(12) **United States Design Patent** (10) Patent No.: **US D1,048,808 S**
(45) Date of Patent: ** Oct. 29, 2024

(54) **BOTTLE**

(71) Applicant: **Take Today Inc**

(72) Inventor: **Zelei Li, Changzi (CN)**

(**) Term: **15 Years**

(21) Appl. No.: **29/871,333**

(22) Filed: **Feb. 16, 2023**

(51) LOC (14) Cl. **07-01**

(52) U.S. Cl.

USPC **D7/392.1; D7/396.2**

(58) **Field of Classification Search**

USPC D7/387, 391, 392, 392.1, 396.2, 396.3, D7/509, 510, 511, 512, 528, 533, 534, D7/536, 601, 602, 619.1, 619.2, 620, 621, D7/622, 623, 624.1, 624.2, 624.3, 625, D7/628, 629, 630, 709, 710, 529, 532, D7/608, 514, 393, 300–322, 603, 605; D9/435, 436, 440, 441, 443, 445, 447, D9/454, 449, 453, 516, 450, 439; D3/201, 202; D24/127; D14/216; D23/233; D26/41; D21/468

(57) **CLAIM**

The ornamental design for a bottle as shown and described.

DESCRIPTION

FIG. 1 is a front elevation view of a bottle showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is a second perspective view thereof.

FIG. 9 is a perspective view of the bottle in an open state of use.

The broken lines depict portions of the bottle that form no part of the claimed design.

1 Claim, 9 Drawing Sheets
